(57) **CLAIM**

The ornamental design for a slender faucet, as shown and described.

DESCRIPTION

FIG. 1 is a front perspective view of a slender faucet of the present invention;

FIG. 2 is a front elevation view of the slender faucet of FIG. 1;

FIG. 3 is a rear elevation view of the slender faucet of FIG. 1;

FIG. 4 is a left side elevation view of the slender faucet of FIG. 1, the right side elevation view being a mirror image thereof;

FIG. 5 is a top plan view of the slender faucet of FIG. 1; and,

FIG. 6 is a bottom plan view of the slender faucet of FIG. 1. The broken lines shown in the drawings are included for the purpose of illustrating a portion of the faucet that forms no part of the claimed design.
